UNITED STATES PATENT OFFICE

JOHN S. HOLLIDAY, DECEASED, LATE OF NEW YORK, N. Y., BY JENNIE MARGARET HOLLIDAY, ADMINISTRATRIX, OF PITTSBURGH, PENNSYLVANIA, ASSIGNOR TO MATTHEW H. LOUGHBRIDGE, TRUSTEE, OF BOGOTA, NEW JERSEY

TRAIN CONTROL SYSTEM

Application filed October 26, 1928. Serial No. 315,314.

This invention relates to train control systems and is shown applied to the intermittent inductive type of control. Its objects are to provide a novel arrangement of inductive control between the vehicle and the trackway apparatus and to apply this control to either two or three position systems, also to include a system of speed control therewith. Other objects of the invention will appear from the following specification and the accompanying drawings, in which Fig. 1 is a diagram of the controlling circuits on the vehicle, Fig. 2 is a transverse elevation showing the relation of the inductors on the trackway and the vehicle to each other, Fig. 3 is a diagram of one arrangement of trackway control that may be used in applying this invention and Fig. 4 is a modified arrangement of the vehicle circuits for securing three position control.

20 This invention is a continuation in part of my co-pending application, Serial No. 477,867, filed June 16, 1921, all the matter claimed herein being disclosed in the original application.

25 This invention includes on the trackway, magnets which are energized when the block is clear to transmit a proceed effect to the vehicle. One pole of each magnet is also used to produce the stop effect on the vehicle unless this is counteracted by a proceed effect. The trackway magnets are of various lengths for the purpose of securing speed control as hereinafter described.

The vehicle is provided with one or more inductors arranged to register with and receive an impulse from the trackway magnet when the latter is energized. This impulse is used to produce the proceed effect. Another inductor on the vehicle registers with one pole of the trackway magnet. This inductor is energized from a source of current on the vehicle and through an inductively coupled connection maintains the proceed effect on the vehicle by energizing the proceed circuit. If this circuit is interrupted, or the

energy therein materially reduced, the translating device in this circuit is moved by gravity to the controlling position, thus setting up a condition of control until an energized magnet is encountered to establish the proceed condition. The proceed circuit is interrupted for the purpose described by changing the magnetic circuit of the inductor so that the flux is at least partially deflected from one of the inductively coupled coils. The reluctance of the magnetic circuit of the inductor is so influenced by the iron of the track magnet that this result is secured as the vehicle passes over the track magnet. This changes the system from proceed to stop.

50 The track magnets are varied in length so that the duration of the impulse received therefrom is used to operate a time-responsive device whereby speed control may be imposed upon the vehicle control.

55 In the drawings, the track rails are indicated by 11-11, the track magnets generally by 12 located at the entrance to blocks A and B and 12a and 12b indicate track magnets located intermediate the block A. The trackway magnets comprise a pair of poles 14-15, Fig. 2, located parallel with the track rails and energized at intervals by the coils 17 on the magnetic cores 16, the structure being mounted on a stringer 13 which, preferably, brings the top of the magnet poles somewhat above the rail level. The poles may be ramped on the ends as indicated to avoid obstructions on passing trains. This construction, it will be noted, provides an elongated track magnet with a plurality of spaced energizing coils which creates a magnetic field between its poles throughout its length and is thus capable of transmitting a prolonged inductive influence to the vehicle inductors.

60 The track rails are insulated into block sections as shown at A with a source of current 22 at one end and a track relay 21 at the oppo-

50

site end of the block in accordance with each standard track circuit.

The coils 17 of the track magnet are energized from transformer 25 through contact 27 of track relay 21, wire 28 and wire 29 to common return wire 24. These coils are energized when the track relay is energized and are deenergized when this relay is deenergized. The intermediate track magnets are energized by coils 17a and 17b connected in multiple circuit between wire 28 and the common wire 29. These coils are energized when block B is clear and are deenergized when this block is occupied.

15 The vehicle is provided with a pair of inductors 41 terminating in poles 42 which align with the poles of the track magnet as shown. These inductors are provided with coils 45 in which a current is induced when the track magnet is energized, but at all other times are deenergized. These coils are connected in multiple circuit through wires 46 and 47 with the translating device 48 and the condenser 49 may be connected in multiple circuit with this relay. If coils 45 are energized, relay 48 closes the circuit at 72 to establish the proceed conditions on the vehicle.

It will be noted from Fig. 1 that both the inductors 41 are influenced by the track magnet at the same time and the sum of these influences are used to pick up relay 48. This relay is of the tractive type and when its armature is once picked up, less energy will hold it in this position so that as the vehicle passes over the magnet and one of the inductors has passed beyond its influence, the other inductor will maintain the proceed condition already established. Another advantage from the use of two inductors arises from the fact that the stop inductor 51 is placed between the proceed inductors 41-41 so that a proceed inductor is always last to receive influences from the track magnet as the vehicle runs with either end leading.

45 A source of energy is provided on the vehicle as indicated by battery 31 controlled by the double-pole, double-throw, switch 32 which, through wires 35 and 36 drives the motor 33 which is mechanically connected with the A. C. generator 34. Through wires 61 and 62 this generator energizes the primary coil 56 of the stop transformer 51. Through the magnetic yoke 51, the coil 57 on one leg or core of the yoke is inductively coupled with coil 56 on another leg or core of the yoke and is energized as a secondary coil thereby energizing wire 64 which controls the translating signal device 70 through contact 65 of relay 84 energized, wire 66, stick contact 67 of device 70 energized and return on wire 71 and by common wire 61 to coil 57. Thus, if the device 70 is energized to close the contact 67 it will remain energized as long as coil 57 is energized.

65 This maintains the proceed condition after

it has been established. The proceed condition is established by relay 48 closing the circuit at 72 between wires 69 and 62, this being the pick-up circuit for device 70.

A direct current circuit is established from battery 31 through wire 82, coils 54, wire 83, relay 84 and wire 81 to battery. This energizes coils 54 on the extended legs on the magnetic yoke 51. These legs terminate in the poles 52 and 53 which align with one pole 12 of the track magnet. Normally the magnetic circuit between poles 52 and 53 has considerable reluctance through the air gap between these poles and the magnetic influence of coils 54 does not materially influence the inductive relation between coils 56 and 57. As soon, however, as poles 52 and 53 come under the influence of the pole of the track magnet, this reluctance is thereby reduced to such an extent that the D. C. field created by coils 54 tends to saturate the core of coils 56 and 57 and, at the same time the flux created by the primary coil is partially deflected from coil 57 through the poles 52 and 53 to the magnetic iron 12. The conditions described, including the saturation of core of 56 and 57, suppresses the A. C. flux through 57 and thereby deenergizes 70 to produce the stop effect.

As the coils 54 are used to aid in producing the stop effect it is necessary to insure the integrity of these coils. This is secured by relay 84 connected in series with the coils and controlling the holding circuit of 70 at 65. If coils 54 become deenergized a stop effect will be produced by contact 65. Attention is directed to the fact that the core of the secondary coil 57 is provided with a non-magnetic gap so that normally a certain degree of reluctance exists in this core which facilitates deflecting the flux through the track armature 12. It will be observed that the A. C. flux from 56 is continuously supplied to the magnetic yoke 51 including core 57 and the poles 52-53 and, normally the reluctance through 57 is less than through the poles 52-53 so that the translating device 70 is maintained continuously energized as the train passes along the track by the flux in core 57. However, when the poles 52-53 align with the track armature 12, the reluctance through 52-53 is relatively less than through 57 so that coil 57 is substantially deenergized, or sufficiently deenergized to release the armature 67 of 70.

Connected in multiple circuit with the signal device 70 on wires 66 and 71 are the slow releasing relay 75 and the quick acting relay 76. These relays are not controlled by a stick circuit, they are simply deenergized during the time 57 is deenergized that is, during the transit of 51 over the track magnet, but 75 does not release its contact finger until after a given time interval.

When relay 76 is deenergized a circuit is

established from battery on wire 81 through contact 93 and wire 94 to bell 95 and return by wire 82 to battery. This produces an audible signal each time that stop inductor

51 comes under the influence of the track device without regard to whether the block is clear or occupied. This gives an intermittent indication, as the vehicle proceeds over the trackway, that the system is functioning properly.

10 The deenergizing of relay 76 also closes a circuit from wire 81 through 96 and wire 101 to the brake valve 98, the return circuit being by wire 99 to battery. This insures 15 that while 76 is deenergized, that is, during the transit of the stop inductor over the track device, the brake valve magnet is prevented from becoming deenergized to apply the brakes.

20 The brake valve magnet 98 is normally controlled by the stick relay 86 through wire 101, contact 100 and wire 81 to battery. Thus, with relay 86 deenergized and relay 76 energized the valve magnet 98 is deenergized to 25 produce a controlling effect.

The brake valve controlling relay 86 has a pick up circuit as follows: battery, wire 82, relay 86, wire 87, contact 88 of signal device 70 and wire 81 to battery. This relay 29 is thus energized as long as signal device 70 is energized. A stick circuit is provided for this relay through contact 91, wire 92, contact 93 of relay 76 and wire 81 to battery. Thus, relay 86 cannot be deenergized unless 35 relay 76 is at least momentarily deenergized at the same time that 70 is deenergized. A manual release is provided in the form of contact 90 which may be manually operated to connect the pick-up circuit on wire 87 to battery on wire 81, for energizing relay 86. 40 Another pick-up circuit is provided for relay 86 through the back contact 89 of the timing relay 75 which connects wire 87 with the battery wire 81 when relay 75 is in the deenergized position.

45 Speed control is obtained through the timing relay 75 as operated by the trackway magnets of various lengths. For instance, the inductor 51 on passing the track armatures 12 deenergizes relay 75 and this relay closes its back contact after the lapse of a fixed time interval for which it is set to work. If the track armature is of such length that the train at a given speed consumes a time 55 interval greater than the time interval of relay 75 it will close the pick-up circuit of relay 86, but, on the other hand, if the speed of the train is in excess of the permissible speed, relay 75 will not have sufficient time to function and relay 86 will not be energized by relay 75. The permissible speed on the trackway is determined by the length of the track armatures 12, 12a, 12b, etc., so that the permissible speed can be varied to suit track and 60 block conditions by varying the lengths of 65

these armatures. This system of speed control using ramps on the trackway is fully disclosed in U. S. Patent 1,299,595, April 8, 1919.

70 The operation of the system is as follows: When the track is clear the trackway magnets are energized and the inductors 41 energize relay 48 closing the circuit at 72 during the time these inductors pass over the track magnet. At the same time the stop inductor 75 51 deenergizes relay 75 and 76 and the audible signal 95 is sounded. The signal device 70 is maintained energized by relay 48 and this, in turn, maintains relay 86 and valve 98 energized. Thus, the only effect obtained 80 at a clear magnet is the sounding of the audible signal. As the vehicle devices pass off the ramp or magnet the energy is restored in the secondary coil 57 before the last proceed inductor 41 leaves the influence of the track magnet with the result that the holding circuit of 70 is energized before the pick-up circuit is interrupted at 72. This maintains normal clear conditions in the system 85 until the next trackway magnet is encountered. 90

95 When the block in advance is occupied the trackway magnets are deenergized and the stop conditions of control are established. Under these stop conditions there is no energy to pick up relay 48 and coil 57 becomes substantially deenergized. This deenergizes signal device 70, and relays 75 and 76, also relay 86. The audible signal 95 is sounded and the valve 98 is maintained energized. 100 When the vehicle passes away from the influence of the track magnet coil 57 is again energized and relay 76 is energized, also relay 75, but the signal device 70 and relay 86 remain deenergized; this deenergizes the 105 brake valve magnet 98 and effects the stop condition of control on the vehicle which continues until the manual release 90 is operated to pick up relay 86.

110 If the speed of the vehicle when passing over a deenergized magnet is such as to effectively deenergize relay 75 during the transit of the train by the magnet relay 86 will be energized by contact 89 and brake valve magnet 98 will remain energized and thus prevent the stop control conditions becoming effective; the signal device 70 however will continue to indicate stop. Thus, by maintaining a predetermined low speed 115 120 the conditions of stop control can be avoided, but an indication of danger conditions is continuously displayed.

125 When the vehicle apparatus in the controlling condition encounters an energized trackway magnet the relay 48 is energized; this energizes 70 and changes the indication from stop to clear, also relay 86 is energized and the valve magnet 98 is energized. When the vehicle passes beyond the magnet, relays 130

76 and 75 are energized and clear conditions are resumed.

When the double-pole, double-throw switch 32 is reversed the system is suspended by deenergizing all the apparatus except brake valve magnet 98 which is then connected directly to battery 31.

It should be noted that in practice coil 57 is not deenergized in the sense that it would 10 be deenergized if its circuit were opened. The flux normally passing through the core of this coil is deflected to an alternative path through armature 12 to cause such a drop or difference in current in the circuit as to release the translating devices connected to this 15 circuit. This effect is also materially assisted by the direct current flux suppressing the alternating current flux through the same core. The back contact 96 is designed to 20 close before the front contact 93 of relay 76 opens. This prevents an interruption in the circuit of brake valve magnet 98. The inductor 51 has been referred to as the stop inductor; this, however is merely a convenient term as in addition to producing the 25 stop effect, this device actually maintains the apparatus in the proceed condition as the train passes between magnet locations.

The modification in Fig. 4 includes a three 30 position control for producing the stop effect; the proceed effects may be obtained in various ways some of which are disclosed in the parent application, but for the sake of simplicity are omitted from this drawing.

35 The stop transformer 51 is provided with poles 52 and 53 which align with the track armature 12. The primary coil 151 is connected with the generator by wires 61—62, and the common wire 61 connects to the block 40 relays 139—140.

A pair of independent secondary coils 152a and 152b are provided on core 152. One side of these coils is connected to the common wire 61, the opposite side of coil 152a connects by wire 153 through contact 155 with 45 the stick circuit of block relay 140 and the opposite side of coil 152b connects by wire 154 with contact 156 of block relay 139. It is apparent that under normal conditions 50 the primary coil will energize the secondary coils and thus energize the stick circuit of each of the block relays. But when the poles 52 and 53 align with the trackway armature 12 the flux through core 152 is at least partially deflected to 12 and the secondary coils 55 are correspondingly deenergized and the block relays are thereby released. An air gap is provided in core 152 as shown to increase the reluctance of this core and make 60 it correspond with the air gap between the poles 52—53 and the trackway armature.

Attention is directed to the fact that the trackway armature is laminated as indicated in Fig. 2 and is therefore easily saturated 65 by the A. C. flux while the regular solid iron

of the trackway has considerable reluctance to the A. C. flux.

Block relay 139 is energized by a proceed circuit continued on wire 136 and block relay 140 is energized by a proceed circuit continued on wire 138; these circuits are not shown on the drawings.

The three position signal device 110 is controlled by the block relays. When both of these relays are energized, the light G is 75 energized by wire 164, when both of the block relays are deenergized, the indication R is energized by wire 173 and when either relay is energized and the other deenergized, the indication Y is energized by wire 169. 80

It is understood that the principles of the invention are capable of application in a variety of ways and are not limited to the construction shown and described.

Having thus described the invention, it is 85 claimed;

1. In a railway traffic controlling system, a track, a vehicle thereon, a device on said track of a predetermined length, a controlling mechanism on said vehicle, a transformer device on said vehicle co-operating with said track device, and a slow releasing relay and a quick releasing relay connected to the secondary circuit of said transformer device, said relays operating said train controlling 90 mechanism in accordance with the predetermined length of said track device and the speed of the vehicle.

2. In a railway traffic controlling system, a track, a vehicle thereon, a braking mechanism on said vehicle, devices on said track of various lengths, a transformer device on said vehicle cooperating with said track device, a time element relay and a quick releasing relay associated with the secondary of 100 said transformer device, said quick releasing relay controlling said braking mechanism to stop the vehicle and said time element relay preventing the operation of said braking mechanism.

3. In a railway traffic controlling system, a track, a vehicle thereon, a device on said track, a stick relay, a transformer device on said vehicle cooperating with said track device, a quick releasing relay and a time element relay associated with the secondary of 110 said transforming device, said quick releasing relay deenergizing said stick relay and said time element relay energizing said stick relay.

4. In a railway traffic controlling system, a track divided into blocks, a vehicle thereon, a braking mechanism on said vehicle, a device on said track energized by current controlled by said blocks, a transformer device on said vehicle cooperating inductively with said track device to operate said braking mechanism, means operated by said transformer device for preventing the operation of said braking mechanism after a predeter- 125

mined time interval and means for preventing the operation of said braking mechanism when said track device is energized.

5. In a railway traffic controlling system, the combination, a track with a vehicle thereon, devices on said track of various lengths, devices on said vehicle responding inductively to said track devices and operating a quick acting device and a slow acting device on 70
10 said vehicle, a controlling mechanism on said vehicle, a stick relay controlling said mechanism, said stick relay deenergized by said quick acting device, said controlling mechanism energized by said quick acting device 75
15 and said stick relay energized by said slow acting device.

6. In a train controlling system, the combination, a track with a magnetic device thereon, a vehicle on said track having an inductor moving in inductive relation to said magnetic device, said inductor comprising a plurality of magnet cores connected by a magnetic yoke and having a primary coil on one core and a secondary coil on another core, train control means normally energized solely by said secondary coil and means whereby said secondary coil is substantially deenergized by said magnetic trackway device.

7. A car element for train control systems comprising, a source of alternating current and two partial magnetic circuits of normally different reluctances, both energized from said source and a coil on each of said magnetic circuits coupled in inductive relation 95
30 to each other and a translating device energized solely by the current in one of said coils.

8. A car element for automatic train control systems comprising, a yoke of magnetic material of configuration resulting in two parallel magnetic circuits terminating in a pair of poles one of said magnetic circuits having a lower reluctance than the other, means for continuously supplying undulating flux to said circuits, a coil on said magnetic 100
40 circuits energized by said flux, a translating device normally energized by current in said coil and trackway means having means for varying the electrical characteristics of said magnetic circuits.

50 9. A car element for automatic train control systems comprising, a yoke of magnetic material having two partial magnetic circuits one of which has a lower reluctance than the other, means for continuously supplying alternating flux to said circuits, and a circuit normally energized by said alternating flux to the extent of the relative values of these reluctances.

60 10. A car element for automatic train control systems comprising, a yoke of magnetic material of a configuration resulting in two partial magnetic circuits, one of which has a lower reluctance than the other, means for constantly supplying alternating flux to said 110
55 circuits and a circuit normally energized by

said alternating flux to the extent of the relative values of these reluctances.

11. In a railway traffic controlling system, the combination, a track, magnetic devices on said trackway, a vehicle on said track having a controlling mechanism, means on said vehicle responsive inductively to said trackway devices, a circuit controlled by said means and an electrically operated timing device embodied in said circuit and operated by 75
75 said magnetic devices only during the time said vehicle means is responsive to said trackway devices to control the speed of said vehicle.

12. In a railway traffic controlling system, the combination, a track divided into blocks, magnetic devices of various lengths on said trackway controlled by said blocks, a vehicle on said track having a controlling mechanism including a timing device, and means on the vehicle responsive inductively to said magnetic devices and operating said timing device, said timing device co-operating with said magnetic devices to control the speed of 80
85
90 said vehicle.

13. In a railway traffic controlling system, the combination, a track divided into blocks, magnetic devices of various lengths on said trackway controlled by said blocks, a vehicle on said track having a controlling mechanism including a timing device, and means on said vehicle responding inductively to said magnetic devices and operating said timing device, said timing device controlling the speed 95
100
105 of said vehicle at each magnetic device when the track is not clear and means for giving a signal on the vehicle at each trackway device encountered.

14. A vehicle device for a train control system comprising a magnetic yoke with a pair of coils inductively coupled thereon, means for energizing said yoke with an alternating flux and means for saturating said yoke with a direct current flux.

15. A vehicle device for a train control system comprising a magnetic yoke with a pair of coils inductively coupled thereon, a source of alternating current for energizing said coils, another coil on said yoke on an independent circuit and means for energizing 110
115 said last named circuit with direct current.

16. In a train control system, the combination of a trackway and a vehicle, a magnetic yoke on said vehicle energized with an alternating flux, a controlling mechanism associated with said yoke, and means on the trackway for causing a saturation of said yoke with a uni-directional flux.

17. A transformer device to be influenced when passing a body of magnetic material comprising a yoke of magnetic material of such form as to have two partial magnetic circuits with a portion common to both circuits, one circuit having a short reluctance gap therein, the other circuit having a long 125
130

- 5 reluctance gap adapted to be bridged in passing a body of magnetic material to thereby shunt the first named circuit, an energizing coil on said portion of the yoke for inducing magnetic flux in both circuits, a secondary coil on another portion of the yoke included in the first named magnetic circuit and deprived of energy when the second named circuit is bridged by said body of magnetic material, and translating means connected in circuit with the secondary coil and normally energized by said energizing coil.
- 10 18. A transformer device to be influenced when passing a body of magnetic material comprising a yoke of magnetic material having a plurality of legs so arranged as to provide two partial magnetic circuits with a portion common to both circuits, one circuit including two of said legs with a short reluctance gap between them, the other circuit including two of said legs with a long reluctance gap between them adapted to be bridged in passing a body of magnetic material to thereby shunt the first named circuit, an energizing coil on said portion of the yoke for inducing magnetic flux in both circuits, a secondary coil on another portion of the yoke included in the first named magnetic circuit and deprived of energy when the second named circuit is bridged by said body of magnetic material, and translating means connected in circuit with the secondary coil and normally energized by said energizing coil.
- 15 19. A vehicle device for a train control system comprising a magnetic yoke with a pair of coils inductively coupled thereon, means for energizing said yoke with an alternating flux and means for saturating said yoke with direct current flux to effectively suppress the alternating flux.
- 20 20. In a train control system, the combination of a trackway and a vehicle, a magnetic yoke on said vehicle energized with an alternating flux, a controlling mechanism associated with said yoke and means on the trackway for causing a saturation of said yoke with uni-directional flux to effectively suppress the alternating flux.
- 25 21. In a train control system, the combination of a trackway and a vehicle, a magnetic yoke on said vehicle energized with alternating flux, a means on said vehicle for energizing said yoke with direct current flux, a translating device associated with said yoke and means on the trackway for controlling said translating device by controlling the flux in said yoke.
- 30 22. In a train control system, the combination of a trackway and a vehicle, a magnetic yoke on said vehicle having a primary coil, and a secondary coil conductively coupled with said primary coil and energized with A. C. flux, a controlling device in circuit with one of said coils and an open magnetic circuit,

a third coil energized by direct current in said open magnetic circuit and means on the trackway for shunting said open magnetic circuit to cause the saturation of said yoke with direct current flux.

70 23. A vehicle device for a train control system comprising a magnetic yoke with a pair of coils inductively coupled thereon and energized with A. C. flux, a translating device connected with one of said coils, said yoke having a pair of depending poles with a third coil thereon energized by direct current and means for varying the magnetic circuit of said depending poles to effect the operation of said translating device.

75 24. A vehicle device for a train control system comprising a magnetic yoke having parallel paths of different magnetic reluctances, a pair of coils inductively coupled on said yoke and energized with A. C. flux, a controlling device in circuit with one of said coils and means for saturating said yoke with uni-directional flux.

80 25. A vehicle device for a train control system comprising a magnetic yoke having a pair of horizontally disposed magnetic members, vertical magnetic connections with extending ends forming poles connecting said horizontal members, a pair of coils inductively coupled on said horizontal members and magnetic means on the trackway registering with said poles for influencing the magnetic flux in said horizontal members.

85 26. A vehicle device for a train control system comprising a magnetic yoke having a pair of horizontally disposed magnetic members, one of which includes an air gap, vertical magnetic connections with ends forming poles connecting said horizontal members, a pair of coils inductively coupled on said horizontal members and magnetic means on the trackway registering with said poles for influencing the magnetic flux in said horizontal members.

90 27. A vehicle device for a train control system comprising a magnetic yoke having a pair of horizontally disposed magnetic members, one of which includes an air gap, magnetic connections with ends forming poles connecting said horizontal members, a pair of coils inductively coupled on said members and a magnetic bar on the trackway parallel with said horizontal members registering with said poles for influencing the flux in said members, said horizontal member with the air gap being placed adjacent said trackway bar.

95 28. A vehicle device for a train control system comprising a magnetic yoke having a pair of parallel magnetic members, one of which includes an air gap, magnetic connections for the ends of said members forming poles, a pair of coils inductively coupled on said members and a magnetic member on the trackway registering with said poles for in-

fluencing the magnetic flux in said parallel members.

29. A vehicle device for a train control system comprising a magnetic yoke having a pair of parallel magnetic members, one of which includes an air gap, magnetic connections for the ends of said members forming poles, a primary coil on one of said members and a secondary coil on the member with the air gap, a translating device controlled by said secondary coil and magnetic means on the trackway for influencing the magnetic flux in said parallel members.

10 In testimony whereof I affix my signature.
